UNITED STATES PATENT OFFICE.

GEORGE H. WOODFIELD, OF TOLEDO, OHIO, ASSIGNOR TO THE TOLEDO BENDING COMPANY, OF TOLEDO, OHIO, A CORPORATION OF OHIO.

CONTROL MEANS FOR WINDOWS OR THE LIKE.

1,315,447.

Specification of Letters Patent. Patented Sept. 9, 1919.

Application filed April 2, 1919. Serial No. 237,051.

To all whom it may concern:

Be it known that I, GEORGE H. WOODFIELD, a citizen of the United States, and a resident of Toledo, in the county of Lucas and State of Ohio, have invented a certain new and useful Control Means for Windows or the like; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates particularly to means for raising and lowering the windows of automobiles, and has for its object the provision of a mechanism of this class which is simple and inexpensive in its construction and composed of a minimum number of parts, is adapted to automatically lock in any position of adjustment to prevent lowering of the window by jarring, is capable of being easily operated, and is noiseless in its action, thereby increasing its practicability and commercial value.

The invention is fully described in the following specification, and while, in its broader aspect, it is capable of embodiments in numerous forms, a preferred embodiment thereof is illustrated in the accompanying drawings, in which,—

Figure 1 is an inner sectional fragmentary elevation of a vehicle with the door thereof equipped with the invention and having its window in lowered position. Fig. 2 is an enlarged detail of the invention with parts broken away and with the operating handle removed. Fig. 3 is a section on the line 3, 3 in Fig. 2, with the operating handle in position. Fig. 4 is an inner side elevation of the inner end portion of the operating handle. Fig. 5 is an enlarged section of the door on the line 5, 5 in Fig. 1. Fig. 6 is a section of the invention on the line 6, 6 in Fig. 3. Fig. 7 is a perspective view of the dog and control handle carrying head, with a part broken away. Fig. 8 is an outer end view thereof. Fig. 9 is a perspective view of the cam member, and Fig. 10 is a perspective view of the locking dog.

Referring to the drawings, 1 designates a vehicle door having a window opening 2 therein, and 3 is a glass or window part

which is adapted to stand in position to close the opening 2 or to be lowered into the lower portion of the door, which is made hollow for such purpose, as is customary in doors commonly used in closed vehicles. The window or member 3 is provided at its lower edge with a horizontal channel 4 in which operates a roller 5 that is carried by a vertically swinging arm 6. This arm is fixed at its inner end to and projects transversely from the inner end of a journal or carrying head 7, which is mounted for rotary movements in a bearing bracket 8. The bracket 8 is disposed within the hollow lower portion of the door 1 and is bolted or otherwise suitably secured to one of the upright edge members 9 of the door. The weight of the window 3 is counteracted by a contractile spring 10, which is connected at one end to a yoke 11 that spans the cylindrical sleeve or bearing portion 12 of the bracket 8 and is attached at its ends to the arm 6 at opposite sides of said bearing sleeve, while the opposite end of said spring is fixed to the opposite edge upright of the door from that to which the bracket is secured. In the present instance the spring 10 is connected to the yoke 11 through the medium of a curved member 13.

The journal head 7 is provided at one end with a flange 14, which coacts with the outer edge of the bearing sleeve 12 to limit its movement therein, and the head is also provided at its end with an auxiliary projecting trunnion 15 on which the hub portion 16 of the control-handle 17 is loosely mounted for rotary movements, being retained thereon by a screw 18. The head 7 is provided in its body portion within the bearing sleeve 12 with a diametrically disposed recess 19 in which a dog 20 is mounted for limited reciprocal movements transverse to the head axis. This dog, in the present instance, is of flat plate-like form and is provided at one end with a transversely projecting lug 21, which extends in parallel relation to the head axis and is adapted to project forwardly through an opening 22 in the head with its outer end projecting without the flange or outer side of the head toward the hub 16 of the control handle. The opening 22 is of greater radial depth than the width of the lug 21 to permit radial movements of the lug therein relative to the head.

The catch end of the dog 20, which is opposed to the end thereof from which the lug 21 projects, is adapted to project beyond the periphery of the head 7 and into catch engagement with the registering notch 23 in the inner periphery of the bearing sleeve 12, a plurality of said notches being provided therein in equi-distantly spaced relation, as shown in Fig. 6. The dog 20 is yieldingly held in engagement with a notch 23 by a coiled compression spring 24, which is disposed in an opening 25 in the dog 20 and is also disposed in an enlargement 26 in the central portion of the recess 19 to adapt it to have one end thrust against the respective end wall of the recess 26 and its other end thrust against the respective end wall of the opening 25 to urge a catch engagement of the dog with a registering notch 23.

20 A cam-plate 27 of disk form, in the present instance, is mounted on the trunnion 15 between the head 7 and the handle hub 16 and is provided with a peripheral notch 28, which straddles the lug 21 on the dog. The notch 28 is of greater width than the lug 21 to permit a limited rocking movement of the cam-plate relative to the lug, and the inner end wall of the notch, against which the inner edge of the lug is held in yielding contact by the action of a spring 24, is of V form to cause said wall to have a camming action on the lug 21 when the plate is moved from neutral position relative to said lug, and to effect a consequent movement of the dog to withdraw its end from locking engagement with a notch 23.

40 The hub portion 16 of the control handle has pins 29 projecting therefrom into registering openings 30 in the cam-plate to cause the plate and handle to have rocking movements together. The handle and plate are normally held in neutral position relative to the head 7 and the dog 20 by a coiled compression spring 31, which is mounted in an opening 32 in the plate 27 and projects laterally therefrom into a registering recess 33 in the adjacent end of the head 7.

50 It is evident that in moving the control handle 17 to effect either a raising or lowering of the window, the handle and plate 27 fixed thereto are first permitted to have a limited rocking movement relative to the head 7 by reason of the play afforded between the sides of the dog lug 21 and plate notch 28, and during such relative movement the cam wall of the notch 28 acts on the lug 21 to effect a withdrawal of the dog 20 from locking engagement with the bearing sleeve 12. During the continued 60 movement of the control handle the head 7 is permitted to turn freely in its bearing to effect a rocking of the arm 6 and a consequent raising or lowering of the window to desired position. Upon a release of the 65 rocking pressure on the handle 17 the

spring 31 acts to return the cam plate 27 to neutral position with respect to the dog 20, as shown in Fig. 2, thereby rendering the dog free to enter one of the notches 23 in the bearing sleeve and thus prevent a 70 further movement of the window until the control handle has again been rocked to move the dog to released position.

75 The control mechanism is practically noiseless in its action as the parts thereof are prevented from rattling by the action of the holding springs, and the dog is positively held out of notch engaging position when the carrying head 7 is being shifted in one direction or the other, thereby permitting the locking dog from clicking past coacting notches in the bearing sleeve.

80 I wish it understood that my invention is not restricted to any specific construction, arrangement or form of the parts, as it is capable of numerous modifications and changes without departing from the spirit thereof as defined in the claims, and also that while I have particularly illustrated my locking means in connection with an 90 automobile door, it may be used in other connections.

85 Having thus described my invention, what I claim as new, and desire to secure by Letters Patent, is,—

95 1. In combination, a journal bearing having a series of internal catch notches, a journal rotatably mounted in said bearing, a dog carried by the journal and normally engaging one of said notches, and control 100 means mounted for limited movements relative to the journal and operable when moved in either of opposite directions to first move the dog to released position and to then move the journal and dog to a predetermined position.

105 2. In combination, a bearing member having inner catch notches, a cylindrical head journaled in said member, a dog carried by said head for movements transverse to its axis and normally engaging in one of said notches to lock the head against rotation in either direction, control means carried by said head for limited rocking movements relative thereto and for rotation therewith 110 and having a part in camming coaction with a part of said dog to effect a retraction of the dog from notch engaging position when said means has movement in either direction relative to said head, and means for normally retaining said first means in neutral position relative to said head.

115 3. In combination, a bearing member having peripherally spaced internal notches, a cylindrical head journaled in said member 120 and having a transverse opening, a dog mounted in said opening for reciprocatory movements transverse to the head axis and normally engaging one of said notches, said dog having a lug projecting without one end 130

- of said head, and a control member carried by said head for limited rotation relative thereto and having an opening at one side of its axis receiving said lug, one wall of said member opening having camming coaction with said lug to retract the dog to released position relative to said bearing member when the control is turned in either direction relative to said head.
4. In combination, a bearing member having peripherally spaced internal notches, a cylindrical head journaled in said member and having a transverse opening, a dog mounted in said opening for reciprocatory movements transverse to the head axis and normally engaging one of said notches, said dog having a lug projecting without one end of said head, and a control member carried by said head for limited rotation relative thereto and having an opening at one side of its axis receiving said lug, one wall of said member opening having camming coaction with said lug to retract the dog to released position relative to said bearing member when the control is turned in either direction relative to said head, and spring means interposed between said head and con-
- trol member to yieldingly retain them in neutral relation.
5. In combination, a bearing provided internally with an annular set of control notches, a cylindrical head journaled in said bearing, a dog carried internally by said head for movements transverse to its axis, a spring coacting with said dog and head to yieldingly project one end of the dog into engagement with a registering notch in said bearing, a lug projecting from said dog longitudinally of the head, a control lever journaled on an end of said head and having a part provided with a recess receiving said lug and adapted to coact therewith to permit predetermined rotation of the head and lever, said recess having a wall of V form in coaction with said lug to retract the dog to released position when the lever is moved in either direction from neutral position relative to the head, and a spring coacting with said lever and head to normally retain them in neutral relation.

In testimony whereof I have hereunto signed my name to this specification.

GEORGE H. WOODFIELD.
